Application November 8, 1937, Serial No. 173,356

6 Claims. (Cl. 312—190)

This invention relates to cabinets and similar containers, and principally to containers of this kind of the knock-down or collapsible type; and the object of the invention is to provide a cabinet or container of this class with a sliding door for controlling the opening giving access to the interior of the cabinet or container, and more particularly in the provision of means for compactly rolling a flexible corrugated sheet forming 10 said door closure upon a spring roller disposed in such position within the cabinet or container as to not interfere with or obstruct the use thereof; and still further in a manner which is substantially invisible when the closure of the 15 cabinet or container is in open position; a further object being to provide a winding unit consisting of two spring rollers around one of which the flexible closure is adapted to be rolled, and the other of which is adapted to roll a supporting 20 or operating tape or strand serving as the primary means for moving the door from a closed to an open position; whereas the first named roller functions primarily to wind the flexible material of the closure in the operation of moving the 25 same into open position; a still further object being to provide a closure unit for cabinets of the class described, comprising a frame forming the front door frame of the cabinet wherein the sliding door and associated parts constitute a 30 unit part of said frame; a further object being to provide brackets for supporting the rollers of the device with means on said brackets engaging side walls of the resulting cabinet to aid in supporting and reinforcing said brackets in the cabinet; and with these and other objects in view, the 35 invention consists in a cabinet of the class and for the purpose specified which is simple in construction, efficient in use, and which is constructed as hereinafter described and claimed.

The invention is fully disclosed in the following specification, of which the accompanying drawings form a part, in which the separate parts of my improvement are designated by suitable reference characters in each of the views, and 45 in which:

Fig. 1 is a perspective view of a cabinet made according to my invention, showing the top wall in removed position with parts of the construction broken away and in section.

Fig. 2 is a section on the line 2—2 of Fig. 1.

Fig. 3 is a partial section on the line 3—3 of Fig. 1, showing the top wall in position.

Fig. 4 is a perspective view of the upper end portion of a frame unit constituting one part of the complete cabinet.

Fig. 5 is a partial section on the line 5—5 of Fig. 3.

Fig. 6 is a partial section on the line 6—6 of Fig. 1.

Fig. 7 is a front view of a modified form of 5 cabinet which I employ.

Fig. 8 is a partial section on the line 8—8 of Fig. 7, on an enlarged scale; and,

Fig. 9 is a partial section on the line 9—9 of Fig. 7.

In Fig. 1 of the drawings I have shown for the purpose of illustrating one use of my invention, a cabinet consisting of collapsibly related parts consisting of a front frame part 10, forming the front of the cabinet and the frame of a 15 door opening 11, the frame 10 consisting of a top rail 12, a bottom rail 13 and side rails 14. A front closure portion or wall 15 of single-faced corrugated board is arranged at the bottom of the cabinet and includes a top rail part 16 which 20 forms the bottom wall of the door opening 11.

The part 17 of the cabinet consists of foldably related wall members, namely a back wall 18 and two side walls 19, which are foldable with respect to the back wall 18 to form a flat compact package. These walls are preferably composed of cardboard, corrugated board or the like; but may be composed of any other material depending upon the structure desired in the resulting cabinet. In this connection, it will be understood that the wall parts 18, 19 are hingedly united 25 at the intersecting corners thereof to provide for the collapsing of said walls as will be apparent.

The cabinet also consists of two substantially similar top and bottom walls 20, 20a; and the only difference between these walls is the inclusion of a garment hanger 21 in the top wall 20. Otherwise these walls consist of a rectangular sheet 22 of cardboard, corrugated board or the like, having depending flanges 23 at the sides and 30 back thereof reinforced by strips 24 to which the brackets 25 are secured; the brackets serving as supports for the cross-rod 21a of the hanger 21. It will be noted that the brackets 25 are offset inwardly so as to extend into the compartment of the cabinet inwardly of the side walls 19; the upper edges of said wall being recessed as seen at 19a to receive the attached portions of the brackets 25. It is also preferred that the side rails 24 be recessed as seen at 24a to receive 35 hook-shaped flanges 26 on roller supporting brackets 27; the flanges 26 engaging upper edges of the side walls 19 to aid in reinforcing the mounting of said brackets as will be apparent. It is also preferred that the upper edges of the walls 40

10

30

35

40

45

50

55

19 be recessed as indicated at 19b to receive the hook-shaped flanges 26.

The brackets 27 are substantially of identical construction with the exception that one of the brackets will be provided with angular apertures 28, 29, for supporting the usual angular shanks at one end of conventional spring rollers 30, 31, respectively; that is to say, rollers similar to those commonly employed in operating window shades and well known in the art. For this reason no specific illustration of the rollers is herein shown.

The brackets are reinforced by outwardly extending peripheral flanges 32 and are further reinforced by beaded portions 33 to give strength and rigidity to said brackets, the flat surfaces of the brackets being disposed adjacent the ends of the rollers 30, 31 so as to provide free movement of a flexible door or closure member 34 onto said rollers and to guide side edges of said door onto the rollers as will be apparent. The side edges of the door 34, which is composed of a single-faced corrugated sheet; that is to say, a sheet having a smooth inner surface 34a and a corrugated outer surface 34b as will be noted in a consideration of Fig. 3 of the drawings; operate in grooves 14a on the inner adjacent surface of the side rails 14. These grooves open into the cabinet adjacent the top rail 12 as seen at 14b in Fig. 3 of the drawings.

30 The outer peripheral flanges 32a of the brackets are enlarged as seen at 35 by removing portions of the plate of said brackets, and screws or similar devices 36 are passed through the enlarged portions of the flanges 32a in securing the brackets to the side rails 14 as clearly illustrated in Figs. 3 and 4 of the drawings. The hook-shaped flanges 26 constitute extensions of the upper peripheral flanges 32b of the brackets as will clearly appear upon a consideration of Fig. 4 of the drawings.

40 The roller 30 is preferably arranged adjacent the passages 14b, and this roller acts as a guide for the door 34 in the operation of winding the same upon the roller 31. The roller 30 is so arranged as to exert a straight upward pull on the door or closure; whereas the roller 31 winds or rolls the door thereon; and the tension of these rollers will be such as to perform their respective functions. The spring of the roller 31 should 50 be stronger than that of the roller 30 but not necessarily placed under a greater tension.

55 A tape or strap 30a is secured to the roller 30 and the free end thereof is coupled with a bottom rail 37, attached to the lower edge of the door as seen at 30b; the attached end 30b being preferably flared to clear a spring catch 38 engaging the upper surface of the rail 37 to support the door in closed position against the tension of the roller 30 as well as the roller 31. The spring 60 catch 38 is secured to the inner surface of the rail 16 as seen at 39. The catch is so designed as to automatically snap into position to engage the rail 37 in the operation of moving the door into closed position. This catch includes an outwardly projecting release pin 40 which projects through the front surface of the rail 16 and provides means for releasing the catch 38 to permit the door 34 to move into open position.

70 The rail 16 is provided with an upwardly projecting tongue 16a adapted to fit in a corresponding groove 37a in the rail 37 to form a seal and closure between adjacent surfaces of said rails to provide dustproof characteristics to the resulting cabinet. A finger piece groove 37b is also provided on the outer surface of the rail 37 to facilitate

the movement of the door into a closed position.

When the door 34 is released by the spring catch 38, the door will move into its uppermost position primarily by the action of the roller 30 through the tape or strap 30a connected with the bottom rail 37 of the door. The upward movement of the door or the rail 37 thereof is checked by the engagement of said rail with that part of the tape which is wound upon the roller 30; the latter acting as a cushion in checking this upward movement. In this operation, the roller 31 will provide for the winding of the flexible door in its upward movement. It will appear that by arranging the brackets and rollers in the position indicated that this entire mechanism will be substantially concealed when the door is in raised position; it being apparent that the rail 37 will stop at a position substantially adjacent the lowermost edges of the brackets 27. 20

25 In the packing and shipment of the cabinet, it is preferred that the frame 10 will have the brackets, rollers and door assembled thereon; and the folded back and side walls 18, 19, will be arranged upon the rear surface of the frame 10 below the brackets, as will also the top and bottom walls 20, 20a. In assembling the cabinet, it will be understood that the forward edges of the side walls 19 will be placed in grooves 14c provided on the inner surfaces of the rails 14, and 30 the front edges of the top and bottom walls 20, 20a, or the sheets 22 thereof, will rest in grooves formed in the top and bottom rails 12 and 13 in the manner illustrated at 12a in Fig. 3 of the drawings. Tacks or nails will be employed in 35 securing the side walls and top and bottom walls in position and also in securing the flanges 23 of the top and bottom walls to the upper and lower edges of the back and side walls 18 and 19.

40 In Figs. 7 to 9 inclusive, I have shown a slight modification which is adaptable for use primarily in connection with cabinets of a wider construction. In Fig. 7 of the drawings, I have shown diagrammatically at 41 such a cabinet which differentiates from the cabinet shown in the other figures primarily in the provision of a central rail 42 in the front frame 43 of the cabinet. This frame is otherwise the same in construction as the frame 10; the center rail 42 having grooves 44 on opposite sides thereof for receiving adjacent edges of two similar door members 45, 45a; the other side edges of said door members engaging the side rails of the frame 43 as with the structure shown in said first named figures. With this construction, it will be apparent that 50 two independent pairs of rollers may be provided. However, it is preferred to use single rollers 46 and 47; mounted in brackets 27a, similar to the brackets 27. A double flange wheel or spool 48 is mounted centrally of the roller 47 so as to keep 60 the adjacent edges of the flexible doors 45, 45a, in spaced relation to each other in the operation of winding the same upon the roller 47. Independent straps or tapes 49 will be employed on the roller 46 and coupled with the bottom rails 65 50, 50a, of the doors 45, 45a.

70 I also employ a cross-strap or coupling member 51 for joining the bottom rails 50, 50a, of the doors 45, 45a, across the back of the central rail 42 so that both doors 45, 45a, will operate in unison. The connecting strap or coupling 51 will provide means for engaging a spring catch 52, similar to the catch 38, which may be released by a pin 53, similar to the pin 40.

75 The construction shown in Figs. 7 to 9 inclusive,

will provide a stronger front wall structure for the cabinet, and will provide greater rigidity to the door or closure employed.

It will be apparent that the doors 34 and 45, 5 45a, may be operated from a single spring roller instead of the dual spring roller construction employed, in which event, the rollers 30, 46, respectively, would not include the operating tapes but would simply act as guide rollers over which the doors would be free to pass. However, in this 10 event, the tension of the single spring roller employed would have to be sufficient to perform the two distinct functions; namely, operation of the door, and secondly, winding of the door upon the roller. I find however, that the use of the two spring rollers, each performing its independent function, will provide a smoother and more efficient door operation. The use of a single 15 spring roller as stated would save somewhat in the cost of constructing the cabinet and may be used in certain types of cabinets.

The invention as herein disclosed illustrates a simple and collapsible form of construction for carrying my invention into effect. However, it 20 25 will be apparent that my invention is also applicable to cabinets of more expensive and of different types and construction.

It will be understood that my invention is not limited to any particular arrangement of the 30 rollers in the cabinet so long as one spring roller will operate to move the door in one direction in controlling the door opening of the cabinet and the other roller will operate to wind the flexible door into a small compact roll, preferably arranged adjacent the front open end of the cabinet. It will also appear that in using conventional spring rollers, the usual pawls need not necessarily be employed for holding the rollers against rotation in view of the fact that the 35 door in general use requires only one movement and the spring catch devices, 38, 52, will take the place of such usual pawls.

It will also appear that various types of catch devices and releasing means therefor may be 40 45 employed; these devices being arranged in the cabinet to be consistent with the manner of arranging the spring roller or rollers in the cabinet in imparting movement to the door in one direction. I have also found it desirable to pre-roll the strip of flexible material, for example the single-faced corrugated board, so as to facilitate easy rolling operation of the door upon the receiving roller.

Having fully described my invention, what I 50 claim as new and desire to secure by Letters Patent, is:

1. A knock-down cabinet consisting of back, side, and end walls and a front wall unit detachable with the side and end walls of the cabinet, said unit comprising a frame having top, bottom and side rails forming a large door opening in said frame, inner opposed surfaces of the side rails having longitudinal grooves throughout the length thereof, a flexible door slidably engaging the grooved side rails and forming a closure for said door opening, means secured to the inner surface of the frame adjacent one end thereof and at the side rails of the frame for supporting two rollers within the cabinet adjacent one end of the door opening in said frame, one of said rollers being of the spring type and having one end of the flexible door coupled therewith to be wound on said roller in the movement of the door from a closed to an open position, 55 the other roller being arranged adjacent the first

named roller and the door opening in the frame, the side rails having passages opening into the grooves and through the inner surfaces of the rails adjacent the last mentioned roller to guide the flexible door into and out of the grooves of said rails, the free end of the flexible door having a reinforcing strip slidably engaging the grooved side rails, and means engaging said strip to hold the door in closed position against the action of said spring roller.

2. A knock-down cabinet consisting of back, side, and end walls and a front wall unit detachable with the side and end walls of the cabinet, said unit comprising a frame having top, bottom and side rails forming a large door opening in said frame, inner opposed surfaces of the side rails having longitudinal grooves throughout the length thereof, a flexible door slidably engaging the grooved side rails and forming a closure for said door opening, means secured to the inner surface of the frame adjacent one end thereof and at the side rails of the frame for supporting two rollers within the cabinet adjacent one end of the door opening in said frame, one of said rollers being of the spring type and having one end of the flexible door coupled therewith to be wound on said roller in the movement of the door from a closed to an open position, the other roller being arranged adjacent the first named roller and the door opening in the frame, the side rails having passages opening into the grooves and through the inner surfaces of the rails adjacent the last mentioned roller to guide the flexible door into and out of the grooves of said rails, the free end of the flexible door having a reinforcing strip slidably engaging the grooved side rails, means engaging said strip to hold the door in closed position against the action of said spring roller, said first named means comprising sheet metal brackets extending into the cabinet and engaging inner surfaces of the side walls thereof, and another closure for said door opening slidably engaging the rails of said first named flexible door and arranged in the end of the frame opposed to the end supporting said rollers.

3. A knock-down cabinet consisting of back, side, and end walls and a front wall unit detachable with the side and end walls of the cabinet, said unit comprising a frame having a large door opening bounded on opposed sides with grooved edges, a flexible door slidably engaging the grooved edges of the front wall and forming a closure for said door opening, means forming part of said unit for supporting two rollers within the cabinet adjacent one end of the door opening in said frame, one of said rollers being of the spring type and having one end of the flexible door coupled therewith to be wound on said roller in the movement of the door from a closed to an open position, the other roller being arranged adjacent the first named roller and the door opening in the frame to guide the flexible door into and out of said grooved edges of said door opening, means engaging the door to hold the same in closed position against the action of said spring roller, the free outer end of the door having a reinforcing strip, a flexible strap coupled with said strip and extending longitudinally of the door and attached to the second named roller, and means on the strip of said door and on the part of the frame engaged by said strip when the door is in closed position for forming a tongue and groove connection between the door and said part of the frame.

4. A knock-down cabinet consisting of back, side, and end walls and a front wall unit detachable with the side and end walls of the cabinet, said unit comprising a frame having a large door opening bounded on opposed sides with grooved edges, a flexible door slidably engaging the grooved edges of the front wall and forming a closure for said door opening, means forming part of said unit for supporting two rollers within the cabinet adjacent one end of the door opening in said frame, one of said rollers being of the spring type and having one end of the flexible door coupled therewith to be wound on said roller in the movement of the door from a closed to an open position, the other roller being arranged adjacent the first named roller and the door opening in the frame to guide the flexible door into and out of said grooved edges of said door opening, means engaging the door to hold the same in closed position against the action of said spring roller, said flexible door being divided centrally and longitudinally into two door parts, and adjacent edges of said door parts operating in a double-grooved strip arranged in said frame intermediate adjacent edges of said door parts.
5. In a knock-down container of the class described, a closure unit for the open front of the container, said unit comprising an oblong rectangular frame having grooved side rails, a double-grooved rail intermediate the side rails dividing the frame into two door openings, flexible door members controlling said openings, the side edges of said members slidably engaging the grooved rails of said frame in the movement of said members to open and close the door open-

ings, rollers supported on and constituting part of said unit and arranged adjacent one end of the door openings, at least one of said rollers constituting a spring roller for moving the door members in one direction in the door openings, said door members being manually movable in the opposite direction against the action of said spring roller, one of said rollers forming a guide for the door members in moving into and out of the grooved rails, free ends of the door members having reinforcing strips, and means engaging the reinforcing strips of the door members to support the same against the action of the spring roller.

6. A storage cabinet of the class described having a large door opening in one wall thereof, a flexible door member for controlling said door opening, said door member slidably engaging grooved side edges of the door opening, a pair of spring rollers mounted within the cabinet adjacent one end of the door opening in parallel relation to each other, one of said spring rollers being in close proximity to the longitudinal plane of the door opening, one end of the door being attached to one of said rollers and adapted to be wound thereon in moving the door into open position, the free end of the flexible door having a transverse reinforcing finishing strip, means attached to said strip and extending directly to the other of said spring rollers and wound thereon to aid in moving the door from a closed to an open position, and means for retaining the door in closed position against the action of said spring rollers.

HARRY DERMAN. 35
